UNITED STATES PATENT OFFICE.

CHARLES S. BIRD, OF WALPOLE, MASSACHUSETTS.

PAPER TUBE AND METHOD OF MAKING THE SAME.

1,074,926.

Specification of Letters Patent.

Patented Oct. 7, 1913.

Application filed July 11, 1912. Serial No. 708,843.

To all whom it may concern:

Be it known that I, CHARLES S. BIRD, a citizen of the United States, residing at Walpole, in the county of Norfolk and State of Massachusetts, have invented certain new and useful Improvements in Paper Tubes and Methods of Making the Same, of which the following is a specification.

My present invention pertains to an improved paper tube and the method of making the same.

The invention, in so far as it is susceptible of being illustrated, is shown in the annexed drawings, wherein:

15 Figure 1 is a perspective view of the blank from which the tube is formed; and Fig. 2 a similar view of the tube.

20 In the production of paper tubes (especially tubes which are adapted for use in the manufacture of shells) it is desirable and sometimes necessary that the tube shall be of a uniform diameter throughout, shall present a smooth and even surface, that the surface shall be waterproof, and also, in order to make a salable and attractive article, 25 that the color shall appear the same, or substantially the same, over the entire outer surface or face of the tube.

The object of the present invention is to 30 produce such a tube, and by employing the method hereinafter set forth such object is accomplished.

The blank from which the tube is formed is shown in Fig. 1, and comprises a sheet 35 of paper which, of course, is more or less absorptive, the main portion thereof being designated by 1, and the remainder by 2, the latter being colored. The edges of the sheet, as at 3 and 4, will preferably be 40 thinned, or tapered to a thin or feather edge, so that, when the sheet is rolled into tubular form, it will not present any perceptible thickened portion, nor any sharp edge upon its interior or exterior where the 45 edges of the sheet terminate. The completed tube is shown in Fig. 2, wherein 1 designates the body of the blank which forms the main portion of the tube. The outer colored surface is designated in said 50 figure by 2, but owing to the fact that the edges 3 and 4 are thin and merge into the tube, it is impossible to show the same in the completed tube. This sheet may be made in accordance with Letters Patent of 55 the United States numbered 696,131,

granted to me under date of March 25, 1902, the main difference between the sheet shown in said patent and that disclosed in the present application residing in the fact that in the present instance the edges 60 of the sheet are thinned, as above noted.

The surface of the paper will be found to be more or less rough or broken when closely examined, as is the case with all uncalendered paper, and such surface will 65 not, when treated with a waterproofing material, present an even color, but on the other hand, will appear mottled and blotchy thereby producing an undesirable article. To prevent this, and to insure the production of a finished article, the surface of 70 which will present an even color, I subject the surface of the paper to a substance or compound which tends to fill the unevenness in the surface and prevents the waterproofing material from producing a mottled effect. The entire surface may be so treated, or the plain or uncolored surface or the colored surface alone subjected to 75 such treatment.

80 The compound preferably employed comprises a mixture of glue and clay, preferably china clay. Any substance having the property of china clay may, however, be employed in lieu thereof. Thus, for instance, asbestos ground to the fineness of 85 china clay may be employed as a filler, and in so far as the generic invention is concerned it is to be understood that any material capable of acting in the same manner 90 as china clay is to be regarded as the equivalent thereof. China clay, or its equivalent, which is used as a filler, is inert in that it is unaffected by the material employed to make the tube waterproof, and is likewise 95 inert in that it does not directly affect the color, or the coloring matter which is employed.

In the practice of the invention it is 100 usual to apply the compound or mixture to the colored section alone, and after the sheet is formed into a tube the outer surface thereof is burnished. This operation tends to set down any upstanding fibers and to 105 smooth out the unevenness of the clay. The tube thus formed is dipped in paraffin or other suitable waterproofing material, it being understood that in the commercial practice of the invention a number of such tubes are simultaneously treated. Any surplus 110

waterproofing material is removed by placing the tubes in an oven and allowing the same to drain.

The finished tube, as above noted, presents a smooth, highly-finished surface, of an even color over its entire extent, the filler preventing the appearance of spots upon the surface of the tube which would otherwise be present, owing to the absorption by the tube of the waterproofing material. Whatever may be the action of the materials, the fact remains that without the use of the clay or other substance which, for want of a better term, may be denominated an inert filler, the tube would present a mottled or unevenly-colored surface. It is conceivable, of course, that the colored surface, after being covered with clay, might be at once burnished before the sheet is formed into a tube.

When speaking of the surface of the paper or sheet as being more or less broken or rough, it is, of course, to be understood that the paper employed is not produced from the expensive stock, though the paper should be strong. Stated in another way, the surface may be said to present a series of uneven depressions and ridges, as will appear to a greater or less extent upon the surface of any paper when examined under a glass. The use of the filler or clay tends to fill up such depressions and, as above set forth, prevents the waterproofing material from producing a mottled effect upon the surface. It is to be understood that, in so far as the generic invention is concerned, a paper without any colored section may be employed, and, furthermore, that if a color other than that which would naturally be produced by the paper is desired, it may be brought about by the use of colored clay. Again, it will be understood that the tube may be colored after the sheet is brought into tubular form.

Having thus described my invention, what I claim is:

1. The method of making waterproof paper tubes, which consists in treating a sheet of paper with an inert filler applied to one face thereof; bringing the sheet into tubular form with said treated face outermost; and finally waterproofing the same.

2. The method of making waterproof paper tubes, which consists in treating a sheet of paper with an inert filler applied to one face thereof; bringing the sheet into tubular form with said treated face outermost; burnishing it; and finally waterproofing the same.

3. The method of making waterproof paper tubes, which consists in coloring a section of a sheet of paper; filling one face of such colored section with an inert filling; bringing the sheet into tubular form with the filled face outermost; burnishing the same, and finally waterproofing the tube.

4. The method of making waterproof paper tubes, which consists in producing a colored strip along one side of a sheet of paper; treating such portion with an inert filler to produce a filled face or surface; forming the sheet into a tube with the filled face outermost; burnishing the same; and finally waterproofing the tube.

5. The method of making waterproof paper tubes, which consists in producing a colored strip along one side of a sheet of paper; treating such portion with a surface filler composed of clay and glue; rolling the sheet into tubular form with the treated face outermost; burnishing the outer face of the tube; and finally waterproofing the same.

6. The method of forming paper tubes, which consists in applying an inert filler to the outer face of a tube; and finally subjecting the tube thus treated to a bath of waterproofing material.

7. The method of making waterproof paper tubes, which consists in producing a colored strip along one side of a sheet of paper; treating such colored portion with an inert surface filler; wrapping the sheet into tubular form with the treated face outermost; dipping the tube into a bath of melted waterproofing material; and finally subjecting the tube to heat to remove the excess waterproofing material.

8. As a new article of manufacture, a tube formed from a sheet of paper, the outer surface of the tube being colored and said surface being filled with an inert substance, and being waterproof, the tube being distinguishable by being of an even color over its entire outer surface.

9. As a new article of manufacture, a paper tube having an inert filler applied to and filling the outer surface thereof, such surface being waterproof, the tube being distinguishable by being of an even color over its outer surface.

In testimony whereof I have signed my name to this specification in the presence of two subscribing witnesses.

CHARLES S. BIRD.
